FOREIGN PATENT DOCUMENTS

WO D043804-008 * 6/1998

Primary Examiner — Angela J Lee

CLAIM

The ornamental design for a stand for a video display, as shown and described.

DESCRIPTION

FIG. 1 is a perspective view of a stand for a video display as seen from the front, bottom and left side;

FIG. 2 is a front view thereof;

FIG. 3 is a rear view thereof;

FIG. 4 is a top view thereof;

FIG. 5 is a bottom view thereof;

FIG. 6 is a left side view thereof; and

FIG. 7 is a right side view thereof.

The broken lines shown in the Figures are for illustrative purposes only and form no part of the claimed design.
